Primary Examiner — Philip S Hyder*Assistant Examiner* — Darlington Ly(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my/our new design.

The broken lines shown in the drawings illustrate a tablet device and portions of the display screen with graphical user interface that forms no part of claimed design.
